THERMAL LATCH CIRCUIT BREAKER WITH
SCREW ADJUSTMENT FOR LATCHESRichard C. Ingwersen, Jackson, Mich., assignor
to Mechanical Products, Inc., Jackson, Mich.,
a corporation of Michigan

Application February 7, 1952, Serial No. 270,335

7 Claims. (Cl. 200—116)

1

This invention relates to improvements in electric switches which employ overload protection and of the kind, as disclosed in the prior patents in my name, No. 2,485,736 patented October 25, 1949, No. 2,513,564 patented July 5, 1950, and No. 2,514,545 patented July 11, 1950, in which a bimetallic thermal element connected in electrical series with a movable contact assembly is employed, in association with an actuator re-set plunger button and abutment assembly, to form a latch which, by engagement with the abutment, holds the movable contact assembly in closed position but is subjected to the heat of the current flow to disengage the abutment automatically upon the occurrence of a predetermined current overload and thereby release the movable contact assembly to move to open position.

It is an object of the present invention to improve these prior art electric circuit breakers by providing a simple and inexpensive, yet reliable, means for adjusting the thermal element while *in-situ* in the circuit breaker casing, having regard to the degree of engagement of the thermal latch with the abutment, whereby the operation of the thermal latch can be finally set to suit the particular overload current rating involved. In this respect, the construction of the thermal element itself permits fine calibration as to particular current ratings, which, however, the present invention augments by providing for final adjustment of the degree of contact of the thermal latch element with its abutment, and by enabling this to be done when the circuit breaker has been subjected to laboratory test prior to distribution.

It is a further object of the invention to provide an improved mode of assembling the parts which go to make up the actuator plunger and button assembly, which greatly simplifies the assembling operation compared with the prior art constructions.

These and other objects and advantages of the invention, residing in the construction, arrangement and combination of parts, will appear clear from a consideration of the following description with reference to the accompanying drawings and from the appended claims.

In the drawings:

Fig. I is a view of a circuit breaker in accordance with the present invention, showing in side elevation the improved actuator plunger and button assembly, with one half of the casing removed.

Fig. II is a part sectional end view of Fig. I

2

showing the actuator plunger and the cross screw for adjusting the thermal latch element, as well as the opening in one side wall of the casing through which access is possible to adjust the cross screw, and

Figs. III and IV are similar views to Figs. I and II, respectively, but of a modified construction according to the invention.

In the drawings, wherein like parts have been given the same reference numerals, a circuit breaker is shown having the same general features of construction and operation as disclosed in the prior Patent No. 2,485,736.

The movable contacts 10 are carried upon arms 15 12 secured upon a central thermal latch and guide finger assembly mounted for rectilinear and guided sliding movement with respect to a hollow block 14 of insulating material. This block 14 is connected with two further blocks 18 and 20 of insulating material. These blocks, which form the re-set actuator plunger, indicated generally at 16, are secured together in axial adjacent relationship by a central tie screw 22.

25 The block members 14, 18 and 20 are formed with central bores through which the tie screw 22 is capable of being passed. The head 24 of the screw is held against an annular ledge 26 formed in the block member 14, when the screw threaded portion 28 is screwed into a screw threaded boss portion 30 of the block member 20. The block 20 is shaped at its outer end to form a push button accessible by the operator from outside the casing for resetting the thermal latch and guide finger assembly after the same has been released from its normal set position within the casing upon the occurrence of a predetermined current overload conducted to the thermal latch via the contacts 10 and arms 12.

30 40 This block 20 is slidably mounted within a further block structure 21 of insulating material fixedly mounted in the casing section 23, the casing being composed of two similar sections of insulating material secured together by transverse screws, indicated at 25.

45 The bimetallic thermal latch assembly is indicated generally at 32. It has one side 44 of U-shape in electrical series connection with the movable contacts 10 and engageable with an abutment 34 on the fixed block part 21 for holding the latch in the set and latched position, with the movable contacts 10 closed upon their companion fixed contacts 36 against the action of the coil springs 38, which are stressed when the thermal latch is engaged with the abutment, as

55

disclosed in the said prior patents. The springs 38 are connected between the unit assembly, constituted by the connected arms 12 and thermal latch assembly 32, and arms 31 integral with the fixed block 21.

In the constructions illustrated, the thermal latch has only one-sided latching engagement with the abutment, the other side 40 being formed to have sliding engagement against the side surface 42 of an integral part of the block 21.

In both forms of the invention provision is made to adjust the position of the thermal latch part 44 with respect to the abutment ledge 34. Such adjustment involves varying, within fine limits, the extent or distance the edge of the latch part 44 engages the abutment ledge 34 inwardly from the release side of this ledge, that is the side from which the thermal latch disengages under overload. Such adjustment is rendered possible in each case by a screw 46 which is 20 screwed into a cross bore 48 in the block part 14, which cross bore extends through the tie screw 22, whereby the adjustment screw 46 forms the dual purpose of an adjustment screw to adjust the thermal latch part 44 and a lock for the 25 tie screw 22.

In Figs. I and II the adjustment screw 46 is set at an inclination whereas in Figs. III and IV it extends horizontally. In either case, the head 50 of the adjustment screw is exposed to one side of the thermal latch assembly while its opposite end extends through the opposite side of the block 14 and lies against the inside of the thermal latch part 44. Thus, by adjustment of the screw 46, as by a screw driver, it is readily possible to make the screw bear against the thermal latch part 44 to a greater or less extent and thereby vary the position of the latch edge upon the abutment ledge 34. Access to the screw head 50 is possible through an opening 52 in the corresponding casing side wall 54. This opening is so disposed as to be opposite the screw head 50 when the thermal latch assembly is in the extended position as shown in the drawings. Prior to final laboratory testing of a circuit breaker incorporating this screw adjustment feature the opening 52 will be left open so that any adjustment decided as necessary as the result of test can be readily made. Thereafter the opening is closed or sealed. This may be accomplished by screwing a stud 56 into the opening 52, the opening being screw threaded to receive the stud.

Having thus described this invention what I claim as novel and wish to secure by Letters Patent is as follows:

1. In an electric switch having overload protection; casing structure presenting a side wall with an opening therethrough; an actuator plunger reciprocably mounted in said casing and carrying a thermal latch element, said casing structure including fixed abutment structure for engagement by said thermal latch element to hold the element in latched position, and a screw member on said actuator plunger and engageable with said thermal latch element to adjust the 65

position thereof with respect to said abutment structure, said casing opening being so positioned that the said screw member is accessible for adjustment when the said thermal latch element is latched against said abutment structure.

2. An electric switch as claimed in claim 1, said actuator plunger being built-up from separate parts, a tie screw extending through said parts and holding them secured together in assembled relation, said screw member passing through said tie screw to lock the screw in position as well as to permit adjustment of said thermal latch element.

3. In an electric switch having overload protection, casing structure, fixed and companion movable contact means in said casing structure, an actuator plunger mounted in said casing structure, said plunger carrying a thermal element in electrical series connection with said movable contact means and combined therewith to form a slidable unit, said casing including abutment structure engageable by said thermal element to hold the movable contact means closed, spring means connected with said slid- 30 able unit and stressed when said thermal element is engaged with said abutment structure, said slidable unit carrying adjustment means engageable with said thermal element to vary the position of engagement of the element with the abutment structure.

4. An electric switch as claimed in claim 3, said casing structure including a side wall with an opening, said adjustment means being accessible for adjustment through said opening when the said thermal element is engaged with said abutment structure.

5. An electric switch as claimed in claim 3, said actuator plunger being composed of separate parts in axial assembly, a longitudinal tie screw extending through said parts and securing them together in said assembly, said adjustment means comprising a screw member, said screw member extending crosswise through said tie screw in locking relation thereto.

6. An actuator assembly for use in an electric circuit breaker of the kind described, said assembly comprising separate plunger body parts, a longitudinal tie screw extending within and through said parts and securing them together in axial assembly to form a plunger, a bimetallic thermal means mounted on said plunger and including a flexible blade, and a screw element on said plunger and engageable with said blade to effect adjustment thereof in a lateral direction.

7. An actuator assembly as claimed in claim 6, said screw element extending crosswise through said longitudinal tie screw in locking relationship with respect thereto, said screw element being adjustable axially to effect said adjustment of said blade.
